INVENTOR

William A. Johnson,

By E. S. Brown, his Attorney,

UNITED STATES PATENT OFFICE.

WILLIAM ANDREW JOHNSON, OF OLIVER SPRINGS, TENNESSEE, ASSIGNOR OF ONE-HALF TO W. H. SIENKNECHT, OF OLIVER SPRINGS, TENNESSEE.

BARREL-HANGER

965,526.

Specification of Letters Patent. Patented July 26, 1910.

Application filed August 10, 1909. Serial No. 512,153.

To all whom it may concern:

Be it known that I, WILLIAM A. JOHNSON, a citizen of the United States of America, residing at Oliver Springs, in the county of Anderson and State of Tennessee, have invented certain new and useful Improvements in Barrel-Hangers, of which the following is a specification, reference being had therein to the accompanying drawing.

10 This invention relates to barrel supports for stores and the principal object of the same is to provide a barrel support by means of which a barrel may be normally retained beneath a counter, but which may be readily 15 swung from beneath the same so that access may be had to the contents thereof.

In carrying out the objects of the invention generally stated above, it will, of course, be understood that the essential features of 20 the same are necessarily susceptible of changes in details and structural arrangements, but a preferred and practical embodiment of the same is shown in the accompanying drawings, wherein—

25 Figure 1 is a perspective view of a counter showing the improved barrel support in operative position. Fig. 2 is a central vertical sectional view of the barrel support. Fig. 3 is a detail fragmentary perspective 30 view of the upper end of the stationary portion of the barrel support. Fig. 4 is an inverted detail perspective view of an adjusting collar used in connection with the present invention.

35 Referring to said drawings by numerals, 1 designates a counter the under surface of the top of which is provided with a flat disk 2 having a central outstanding socket 3 formed thereon. Said disk is provided with 40 an opening 4 for screw or other fasteners by means of which it may be rigidly but detachably engaged with said counter with its central socket 3 in a pendent position. A similar socket 5 is fastened to the floor directly beneath the socket 3 and has mounted 45 therein a vertically arranged supporting tube 6 the end of which that fits within the socket 5 being rounded and thickened as indicated at 7. The upper end of said tube 6 has one side cut away to provide a notch 8. A rod 9 is slidably mounted within said tube 6 and is adapted to have its upper end mounted in the socket 3 of the counter 1. Said rod passes through an adjusting collar 10 the under surface of which is partially cut

away to provide a recess 11, and a downwardly projecting lug 11' adapted for interlocking engagement with the notched end of the tube 6. A locking screw 12 passes through said collar for engagement with said rod 9 to hold the same in adjusted relation to said tube 6. Said collar is larger in diameter than the tube 6 and overhangs the same so as to provide a broad flat upper surface 13. A barrel holder is rotatably mounted upon said rod 9, said holder being preferably formed of a single length of material bent to form an end eye 14 which surrounds said rod and from which the diverging arms 15 project and which terminate in downturned hooks 16 for engagement over the top edge of a barrel, as shown in Fig. 1. The tube 6 is also provided with a rotatable barrel engaging support, said support having an upper sleeve portion 17 through which a screw 18 projects for holding said support in a predetermined adjusted position on said tube. Said support has its lower portion thickened and inclined outwardly, as indicated at 19, and terminates in an upstanding lip 20 adapted for engagement beneath the lower edge of a barrel, said support having a curved recess 19' on its inner surface which serves to contact with the periphery of the tube 6, and be rotatable therein with said sleeve. The curving of the inner face of the support greatly facilitates the swinging of the barrel when mounted on said support as is also shown in Fig. 1.

In Fig. 1 of the accompanying drawings 90 a large barrel has been shown mounted upon the support, such for example as a sugar barrel. When supporting a barrel of that size, obviously the upper barrel holder is retained above the collar 10. When supporting a 95 smaller barrel, such for example as a flour barrel, said upper holder would be in a lower position, as illustrated in Fig. 2, so that it will rest upon the broad flat upper surface of said collar 10.

100 It will be seen from the foregoing that the improved barrel holder may be quickly adjusted to fit beneath counters of various sizes, after which the barrel holder may be adjusted for the barrel to be supported 105 thereon so that the same may be normally retained beneath the counter, but can be quickly and easily swung from beneath the same when necessary to have access to the interior of said barrel.

2
What I claim as my invention is:—

A barrel swing comprising supports with
5 sockets secured thereto, a tube rotatably
mounted in one of the sockets, a rod vertically
adjustable in said tube and rotatably
mounted in the other socket, a sleeve on the
lower end of the tube having a barrel support
therewith, said sleeve being vertically
adjustable on the tube, said support having
10 a curved recess on its inner face which con-
tacts with and permits of its rotation on the
periphery of the tube, said tube having a
cut-away portion on its upper end to pro-
vide a recess therein, a collar adjustable on
15 said rod having a portion of its lower sur-

face cut away to provide a recess and a
downwardly projecting lug, said lug adapt-
ed to contact with said recess of the tube so
as to lock the tube and collar together, means
for securing the collar to the rod, means for 20
securing the sleeve to the tube, and a double
pronged barrel support rotatably mounted
on said rod, substantially as specified.

In testimony whereof I hereunto affix my
signature in presence of two witnesses:

WILLIAM ANDREW JOHNSON.

Witnesses:

LAURA J. FORSTNER,
ROBT. M. LINDSAY.
